RAZOR BLADE MAGAZINES AND BLADE CHANGERS

James M. Austin, Old Westbury, N. Y.

Application June 3, 1950, Serial No. 165,918

8 Claims. (Cl. 30—40)

This invention relates to improvements in razor blade magazines and blade changers.

It is an object of the inventor to provide an improved razor blade magazine useable both for supplying new blades and for receiving used blades.

It is a further object of the invention to provide a blade changer for use with such a magazine.

With these and other objects, which will appear, in mind, the invention consists in the combinations and arrangements of parts, and details of construction, which will now first be fully described with reference to the accompanying drawing, and then be more particularly pointed out in the appended claims.

In the drawing:

Figure 1 is a top elevation of a magazine embodying the invention in a preferred form;

Figure 2 is a bottom elevation of the magazine of Figure 1.

Figure 3 is a plan view of a blade changer, showing the magazines and razor in place therein and in central longitudinal section through the magazines;

Figure 4 is a plan view of the blade changer element of Figure 3, and

Figure 5 is a detail section on the line 5—5 of Figure 4.

In my previous application Serial No. 159,038 filed April 29, 1950, now abandoned, for Blade Changer, I have disclosed full details of a razor blade changer and magazine. The devices of the present application are similar to those disclosed in the said application, except in the features hereinafter described in detail, and the present specification will be confined to a description of the novel features forming the present invention together with such other features as appear necessary to a full understanding thereof.

In my previous application, Serial No. 54,618, filed October 15, 1948, for Razor and Blade Magazines Therefor, I have also disclosed a razor blade changer and magazine, including a holder for a razor and for new and used blade magazines, together with pusher mechanism for accomplishing a blade change. The present application being concerned with improvements in the blade deflection arrangements for guiding a blade in its passage from the razor into the used blade magazine and to the adaptation of the magazine therefor. The said application, Serial No. 54,618, has now been issued as Patent No. 2,697,276, granted December 21, 1954.

The magazine casing, as shown in Figures 1 and 2, is formed of a single sheet metal blank. The blank edges 1 and 2 are spaced apart to provide a slot 3, running the full length of the casing, and adapted to accommodate a pusher or blade ejector element. Side walls 4 and 5 and bottom wall 6 cooperate to form a generally rectangular sleeve, the ends of which are closed by the end walls 7 and 8. End wall 7 is notched under the slot 3 to accommodate the pusher and end wall 8 is spaced from the top and bottom walls to provide slots for ejecting new blades and receiving used blades. The

2

top wall overhangs the end wall 8 at 9 and 10 to guide a blade being ejected from the magazine and the bottom wall 6 overhangs the end wall 8 to guide a used blade during insertion into the magazine. End walls 7 and 8 have sections 11 slanted with respect to the side walls and the end walls generally, which slanted sections serve to engage the ends of the cutting edges of the blades for holding a stack of blades in position in the magazine and protecting their cutting edges from contact with the side wall 4. A cutout or aperture 12 is provided in the wall 6 adjacent the used blade receiving slot, to accommodate a blade guiding element as later described. The magazine of Figures 1 and 2 is shown in exhausted or used blade receiving condition, the blade positioning spring 13 being seated against the upper wall of the casing for holding a stack of used blades against the bottom wall 6.

As will be apparent the designation of the magazine walls as upper, lower and side walls is arbitrary and for convenience of description, as the magazine may be held and operated in various positions. Figure 3 shows a blade changer plate or frame 20 held in a box, indicated fragmentarily, with a pair of magazines A and B and a razor C in position on the plate. Only the head end and part of the handle of the razor are shown, it being understood that the handle is of usual length.

A pusher 21 is pivotally and slidably mounted on a bar 22 held in brackets 23 struck up out of the plate 20. The pusher has a tongue 23 adapted to enter in the slot 3 of a magazine for ejecting the top blade of a stack from the magazine. By pivoting the pusher back as shown in Figure 4 the tongue 23 is removed from the magazine slot. Pivoting the pusher toward the magazine causes the tongue 23 to enter slot 3 in blade ejecting relation to the top blade of a stack within the magazine as shown in Figure 3, in which the pusher 22 is shown in section through slot 3, 3 of Figure 1.

The new blade magazine A is held in position in the blade changer by projections 24 struck up from plate 20 or fastened thereto and by projections 25 and 26 on a side wall of the magazine. Projection 25 is generally parallel to side wall 5 but is offset to permit it to fit under the plate adjacent a projection 24 in the latter. The arrangements for holding the used blade magazine B are similar but face in the opposite direction.

The new and used blade magazines A and B are identical and interchangeable, apart from the number and position of blades within them. Each time the pusher is operated the top blade 28 of the stack in magazine A will be pushed into the razor C, and will, in turn, push the used blade 29 from the razor into the used blade magazine B. The razor is held in proper position for the change by hooks or ledges 30 fitting over its cap and by a clip 31 fitting in an aperture in its back and the guard is pressed up as by the means shown in my aforesaid copending application, so as to release the blade for the change. As soon as the supply of blades in magazine A is exhausted, the now filled used blade magazine B is discarded and the empty magazine A is placed in the used blade position, a new magazine being substituted for the magazine A. Each magazine may thus serve first for supplying new blades and then for receiving used blades.

The aperture 12 of the used blade magazine B accommodates a deflector 35, which may conveniently be formed by striking up a part of the plate 20 as indicated. This deflector extends into the magazine B beyond the inner surface of the wall 6 for controlling the blade movement during insertion into the magazine. Used blade 29, shown in Figure 3 as partly inserted in the magazine B, is deflected down by deflector 35, squeezing between the deflector and the top blade of the used blade

stack in the magazine. When the blade 28 has been fully inserted in the razor, blade 29 will have been pushed out of the razor and will rest on lip 36. Spring 13 pressing the stack of blades up toward the center and against deflector 35 toward one end, will tend to rotate the blade 29 clockwise so as to hold its trailing end down on lip 36. Lip 36 will be separated from a blade just starting to enter the magazine by a clearance necessary to prevent interference but must also hold the trailing end of a blade resting on it in position for engagement by the leading end of the next blade ejected from the razor. Thus it is important that the lip 36 be located accurately within a fraction of the thickness of a blade. As soon as the next succeeding blade has pushed the top blade past lip 36, the top blade will snap down, clearing the way for insertion of the succeeding blade.

What is claimed is:

1. A razor blade changer comprising means for holding a new blade magazine, a razor and a used blade magazine in aligned position for a blade change, and a substantially rigid blade deflector positioned in the path of a blade entering the used blade magazine.

2. A razor blade changer comprising a sheet metal plate having integral parts struck up to form means for holding a new blade magazine, a razor and a used blade magazine in aligned position for a blade change, and an integral part of the plate also struck up therefrom and forming a substantially rigid blade deflector positioned in the path of a blade entering the used blade magazine.

3. The combination of a razor blade changer comprising means for holding a new blade magazine, a razor and a used blade magazine in aligned position for a blade change, and a substantially rigid blade deflector positioned in the path of a blade entering the used blade magazine, and a used blade magazine having an aperture accommodating the said deflector.

4. The combination of a razor blade changer comprising means for holding a new blade magazine, a razor and a used blade magazine in aligned position for a blade change, and a substantially rigid blade deflector positioned in the path of a blade entering the used blade magazine, and a used blade magazine having an aperture accommodating the said deflector, the deflector and aperture being adjacent the end of the magazine which is next to the razor.

5. The combination according to claim 4, in which the used blade magazine has a blade receiving slot with an edge spaced from the plane of a blade in the razor by less than the thickness of a blade and a wall generally parallel to the said plane and spaced from the said slot, and includes a spring supported by the said wall for forcing a stack of used blades against the deflector to hold the trailing end of the top blade of the stack down on the said edge.

10 6. A razor blade magazine comprising a casing for holding a stack of blades, and having slots in an end wall for respectively receiving used blades and ejecting new blades, a spring for urging a stack of blades against either of two opposite walls of the casing, one of the 15 two said walls having an aperture adjacent the used blade receiving slot for accommodating a blade deflector.

7. A razor blade magazine comprising a casing for holding a stack of blades, and having a longitudinal slot in one of its walls for accommodating a blade ejector, 20 a spring for urging a stack of used blades against an opposite wall of the casing, the last said wall having an aperture adjacent one end for accommodating a blade deflector and the adjacent end wall having a used blade receiving slot.

25 8. A magazine according to claim 7, in which the casing is formed of a single sheet metal blank, the edges of which define the blade ejector slot.
